PRESSURE ADJUSTMENT FOR BOX-STAYING MACHINES AND THE LIKE.

1,272,802.

Specification of Letters Patent. Patented July 16, 1918.

Application filed September 15, 1916. Serial No. 120,293.

To all whom it may concern:

Be it known that we, EDGAR M. HAWKINS and Otto M. Hoch, citizens of the United States, and residents of Rochester, in the 5 county of Monroe and State of New York, have invented certain new and useful Improvements in Pressure Adjustments for Box-Staying Machines and the like, of which the following is a specification.

10 The present invention relates to a pressure adjustment for presses, punching machines, box-staying machines and similar machines wherein a reciprocating actuating part is used and wherein the power is transmitted 15 through said actuating part to the work-performing element only when the latter is in close proximity to the work to be operated upon.

20 The main object of this invention resides 25 in the provision of means for varying the effective length of the actuating means for the work-performing element in machines of the type above referred to, whereby the pressure exerted upon the work may be varied 30 at the will of the operator.

35 In carrying out the object of this invention, means is provided to connect the reciprocating slide which carries the movable work-performing element, to the collapsible 40 link which connects the said slide to the power transmission means or shaft, in such manner that the distance between the point of connection between the actuating element and slide and the point where the power is 45 transmitted to the actuating element may be varied. Furthermore, provision is made for this adjustment in such manner that the pressure-adjusting means for the tucker knife, when the invention is incorporated in a box 50 stayer, will not be interfered with in any way. Other features and advantages of the invention will be referred to in the detailed description of the invention which follows.

One embodiment of our invention is illustrated in the drawings, in which:

Figure 1 is a front elevation of a box stayer having the invention applied thereto;

Fig. 2 is a side elevation of a portion of the stayer; and

50 Fig. 3 is a fragmental detail sectional view showing the manner in which the adjusting pin is constructed and mounted.

The drawings illustrate a box stayer which includes broadly, a frame 1, a stationary

die 2 and a movable die 3, which latter is 55 carried by a suitable slide 4. Mounted in the upper portion of the frame 1 is a power transmission shaft 5. The actuating means for the movable die 3, which takes the form of a pitman extending between the power 60 transmission shaft 5 and the slide 4, comprises an element 6 which is secured to the end of the shaft 5, eccentrically, by suitable means 7. This element 6 is provided with a shoulder 8 which co-operates with a similar 65 shoulder 9 on a second transmission element 10, which latter is pivotally and slidably connected to the element 6 by means of a pin 11 and is provided at its upper end with a finger 12 which is arranged to be wiped 70 by a cam 13, on the transmission shaft 5. The pin 11 is secured to the element 6 and extends into a slot 14 in the element 10, and on this pin is mounted a spring 15 which continuously bears against the element 10 75 and normally tends to move the shoulders 8 and 9 on the respective elements 6 and 10 into engagement with each other, but permits the disengagement of said shoulders when the cam 13 wipes the finger 12 on the element 10. 80 The transmission element 6 extends downwardly from its point of connection with the shaft 5, and at its lower end has an elongated longitudinally extending slot 16 through which extends a pin which includes 85 a member 17. This pin member is rotatably mounted on the movable die 3 in a lug 18 thereon. Extending through the lug 18 and into a circumferential groove 20 in the pin member 17, is a screw 21 which prevents 90 the longitudinal movement of the pin member with respect to the movable die. The diameter of the portion of the pin member 17 which is located within the slot 16 in the element 6, is less than the length of the slot, 95 so that the element 6 may move with respect to the pin member without imparting movement to the movable die 3. The second transmission element 10 is provided, at its lower end, with a circular opening having 100 a bushing 22 therein, through which bushing the pin member 17 extends. This pin member 17 is provided with an eccentric trunnion 23 which projects rearwardly from the element 10, but which is coaxial with the portion of the pin member which is located within the lug 18. This trunnion 23 is revolubly mounted in a second pin member 24,

which, together with the member 17, forms the pin connection between the slide 4 and the actuating means for the movable die, that is to say, the elements 6 and 10. This 5 pin member 24 is secured rigidly to the slide 4 by a set screw 25 and is provided with a block 26 which extends rearwardly from the slide for the accommodation of the adjusting means for regulating the pressure of the 10 tucker knife 30, movably mounted on the rear end of the die 3 for vertical movement therewith. A threaded stem 30', extending upwardly from this knife through an opening in the block 26, carries a pressure spring 15 29 which expands between the under side of the block 26 and the knife 30 for exerting downward pressure on the latter, and also carries above the block 26 an adjusting sleeve 27 and a clamp nut 28 therefor, the said 20 sleeve being operative to adjust the pressure of the spring 29 in usual manner.

Formed on the forward end of the pin member 17 is a notched wheel 31 having a nut 31' cast thereon by means of which the 25 pin member 17 may be rotated. This pin member 17 is held in its various adjusted positions by means of a two-pointed pawl 32 which is normally pressed into engagement with the notched wheel 31 by a flat spring 33. 30 Thus when the movable die 3 is descending, the cam 13 will maintain the shoulders 8 and 9 of the elements 6 and 10 in disengaged relation, but when the die nears the completion of its stroke and is about to apply pressure to the work, the cam 13 is rendered ineffective and the spring 15 operates to reengage the shoulders 8 and 9, so that the further downward movement of the die will cause pressure to be exerted upon the 35 work, as there will be a direct connection between the transmission shaft 5 and the die. However, if resistance is offered to the movable die in its downward movement—as by the presence of the operator's hand between 40 the dies—before the cam 13 disengages the finger 12, the spring 15 will be inoperative to reengage the shoulders 8 and 9, and, consequently, the subsequent rotation of the transmission shaft 5 will result in no direct 45 pressure upon the movable die 3. Under these conditions, the only pressure exerted by the die will be that exerted by the weight of the die itself and its connected parts, and this is overcome in the present case by means 50 of a suitable spring 34, which is attached to the yoke 36 and to an upper portion of the frame 1 by suitable adjustable means 35.

When it is desired to vary the pressure which the movable dies exerts upon the 60 work, the pawl 32 is disengaged from the notched wheel 31 and the pin member 17 is rotated in the proper direction, that is to say, to cause its eccentric portion, which is located between the lug 18 and the trunnion 65 23, to force the element 10 either upwardly

or downwardly. This adjustment of the pin member 17 will vary the effective length of the actuating means for the movable die which includes the elements 6 and 10.

Thus the invention provides, in a machine 70 where a safety device such as described in the present application is used, means for varying the pressure exerted by the work-performing element and provides specifically 75 a composite pin which connects the die-carrying slide of the box-stayer, which is illustrated in the present drawings, to the die actuating element or pitman. The composite pin, as described, comprises a rotatable member and a member stationary with the 80 die-carrying slide, which latter member supports the adjustment means for the tucker knife, and it is, therefore, essential that this member be held stationary with respect to the slide and the said adjustment means. 85

What we claim is:—

1. In a box staying machine, a rotary actuating part, a reciprocating slide carrying a presser die and a cut-off knife, a pitman connection between said actuating part and 90 the slide, means connecting the pitman to the slide including an eccentric pin member rotatably connected with the pitman and a second pin member rigidly connected with the slide and rotatably supporting the eccentric pin member, means for maintaining the eccentric pin member in adjusted position, and adjusting means for the cut-off knife supported by said second pin member. 95

2. In a box staying machine, a rotary actuating part, a reciprocating slide carrying a presser die, a pitman connection between said actuating part and the slide, means connecting the pitman to the slide including an eccentric pin member rotatably connected with the pitman and a second pin member rigidly connected with the slide and rotatably supporting the eccentric pin member, means for maintaining the eccentric pin member in adjusted position, and a work-performing element movable with the slide and having connection with the said second pin member. 100

3. In a box staying machine, a rotary actuating part, a reciprocating slide carrying a presser die, a pitman connection between said actuating part and the slide, means connecting the pitman to the slide including an eccentric pin member rotatably connected with the pitman and a second pin member rigidly connected with the slide and rotatably supporting the eccentric pin member, means for maintaining the eccentric pin member in adjusted position, and a cut-off knife movable with the slide and having connection with said second pin member. 115

4. In a box staying machine, a rotary actuating part, a reciprocating slide carrying a presser die and a cut-off knife, a collapsible pitman connection between said actuating 120

part and the slide, means connecting the pitman to the slide including an eccentric pin member rotatably connected with the pitman and a second pin member rigidly connected with the slide and rotatably supporting the eccentric pin member, means for maintaining the eccentric pin member in adjusted position, and adjusting means for the cut-off knife supported by said second pin member.

5. In a machine of the class described, the combination with a rotary power transmission element and a reciprocating work-performing element, of a collapsible pitman extending between the same, the said pitman including an element connected to the transmission element, an element connected to the work-performing element, and means for causing the positive engagement of said pitman elements, and means for varying the point of connection between the work-performing element and the pitman element connected thereto.

6. In a machine of the class described, the

combination with a rotary power transmission element and a reciprocating work-performing element, of a collapsible pitman extending between the same, the said pitman including an element connected to the transmission element, an element connected to the work-performing element, and means for causing the engagement and disengagement of said pitman elements, and means for varying the point of connection between the work-performing element and the pitman element connected thereto including an eccentric pin member carried with the work-performing element and rotatably connected with the pitman.

Signed at Rochester, in the county of Monroe, and State of New York, this 12th day of September, A. D. 1916.
